and in Austria May 21, 1931

6 Claims. (Cl. 179—27)

The present invention relates to a circuit arrangement for automatic telephone systems in which connections of high as well as low value are set up over the same connecting devices.

In arrangements of this type, known heretofore, the release of the connecting devices, seized for a connection of high value, depends entirely on the station having set up the high valued connection. The result of this is that if a called subscriber has not replaced his receiver at the end of the high valued connection, other connecting devices of importance for the traffic are unnecessarily engaged. This causes undue delays in the setting up of a further call of high value if such a call is to be put through immediately after the end of a preceding high valued connection.

The present invention eliminates these defects by providing the connecting devices with switching means which, without releasing said connecting devices over which the line is seized remove the line guarding against connections of high value, when a subscriber or operator setting up a connection of this type releases a high valued connection.

In comparison to prior arrangements the present invention also provides important advantages particularly with regard to the circuits and service inasmuch as, on the one hand, one single relay is used for carrying out all the special switching operations necessary for the setting up of a connection of high value in the connecting devices and, on the other hand, special switching operations to be performed, at an operator's position, when completing connections of high value are carried out by actuating one and the same switching means. This is achieved by all the special switching operations required for the setting up of a connection of high value being initiated by applying the same potential to one and the same wire of the speaking leads.

The accompanying drawing shows an embodiment of the invention: Connections of high value constitute toll connections extending, for example, from a toll exchange FA to an automatic exchange, for example, exchange B. Connections of low value constitute local connections set up, for example between the two subscribers T_n and T_{n1} connected to the same exchange B. The connecting devices in exchange B comprise a preselector VW, a first group selector IGW and a final selector LW adapted to operate for local as well as toll connections.

The setting up of a toll connection for the subscriber T_n of the exchange B received in the

toll exchange FA will now be described. The operator at the toll position FP who is to complete the connection inserts the plug St in the jack K1 after having received the call number of the required subscriber T_{n1} from the distant subscriber. The insertion of the plug in the jack causes relay C of the repeater Ue to be energized. Relay C closes its contact 26c and thereby seizes the toll group selector FGW1. Relay C1 in this toll group selector is then energized. Relay C1 closes its contact 42c1 and thus prepares the test circuit to the final selector LW2. The operator at the toll position FP now commences to dial. This causes the impulse contact nsi to apply earth intermittently to the a-lead so that relay A of the repeater Ue is energized accordingly in the following circuit: earth, contact nsi, plug St, K1, a-lead, upper primary winding of the repeater Ue, winding of relay A, battery, earth. Relay A is energized and over its contact 4a transmits impulses to the impulse receiving relay A1 of the toll group selector FGW1. This circuit extends as follows: earth, contact 4a, rotary off-normal contact 44w1, winding of relay A1, battery, earth. The toll group selector FGW1 is set to an idle junction line VL in known manner, which junction line leads to exchange B and thereby closes the following test circuit: earth, contact 42c1, windings I and II of relay P1, c-wiper of the toll group selector, junction line VL, off-normal contact 65k2, winding II of relay C2, battery, earth. Relays P1 and C2 are energized in this circuit. Relay P1 in the toll group selector FGW1 switches through the two speaking leads by closing its contacts 40p1 and 41p1 and by short-circuiting its high resistance winding I by means of contact 43p1, guards the seized line in known manner against further seizures. The circuit for the setting of the toll group selector FGW1 is of no importance for the invention and, therefore, have not been shown. Relay C2 in the final selector LW2 is energized and prepares its own locking circuit by closing its contact 66c2.

On the receipt of the first impulse, relay V in the repeater Ue is energized in the following circuit: earth contacts 18c, 12a, winding II of relay V, battery, earth. Relay V being constructed as a slow-acting relay is maintained energized during the impulse series. The upper primary winding of the repeater Ue is short-circuited on the energization of relay V due to the closing of contact 2v so as to improve the impulse transmission and for the same reason

the secondary winding of the repeater is opened by means of contact 3v.

When the toll group selector FGW1 has been duly set to an idle final selector in exchange B, for example, the shown final selector LW2, relay S in the repeater Ue is energized in the following circuit: earth, winding I of relay B2, contact 61y, junction line VL, b-wiper of the toll group selector, contact 41p1, secondary winding 10 of the repeater Ue, contact 29v, winding of relay S, battery, earth. Relay B2 in the final selector LW2 is not energized in this circuit. Relay S prepares a circuit for relay U by closing its contact 11s. The impulse series for the setting of 15 the final selector LW2 is now transmitted. This causes relay A2 in the final selector LW2 to be energized over: earth, contacts 4a, 40p1, a-wiper of the toll group selector FGW1, junction line VL, contact 50v2, winding I of relay A2, battery, 20 earth. Relay U in the repeater Ue is energized in the following circuit after the first impulse: earth, contacts 18c, 14v, 13v, 11s, 9y, 6h, winding of relay U, battery, earth. Relay U is maintained energized over its contact 17u when relay S is disconnected from the b-lead during 25 the impulse series due to the energization of relay V. Relay V is released at the end of this impulse series and is followed by the slow-acting relay U. The following circuit for relay H is completed during the release period of relay U: 30 earth, contacts 18c, 15v, 19u, 16y, winding of relay H, battery, earth. Relay H is maintained energized over its contact 20h. Due to the energization of relay H a potential is momentarily applied to the b-lead which causes relay V in 35 the repeater Ue2 and relay B2 in the final selector LW2 to be energized. The energization of relay B2 in the final selector LW2 causes the final selector LW2 to be changed over for toll traffic. The circuit extends as follows when the potential is applied: earth, winding I of relay B2, contact 61y, junction line VL, b-wiper of the toll selector FGW1, contact 41p1, lower secondary winding of the repeater Ue, contacts 31u, 40 33h, winding I of relay V, battery, earth. Relay V in the repeater Ue opens its contact 29v so that relay B2 in the final selector LW2 cannot be maintained energized over the winding of relay S after the end of the impulse. The release of relay U ends the impulse transmission. This release is initiated by the opening of contact 6h. Relay V is also then released and by closing its contact 29v connects relay S again to the b-lead causing this relay to be re-energized.

On the intermittent energization and deenergization of relay A2 in the final selector LW2, the following circuit for the vertical magnet Hm of the final selector LW2 is set up during the impulse transmission: earth, contact 109a2, winding I of relay V2, contact 110u2, rotary off-normal contact 79w2, winding of the vertical magnet Hm, battery, earth. Relay V2 is also energized in this circuit. It remains energized during the impulse series in the manner of a slow-acting relay. The final selector LW2 raises its switch wipers to the required level. Relay V2 is released at the end of the impulse series. The following circuit is closed for relay U2: earth, off-normal contact 108k2, contacts 107v2, 45 104c2, winding I of relay U2, rotary off-normal contact 79w2, winding II of the vertical magnet Hm, battery, earth. The vertical magnet Hm is not energized in this circuit but relay U2, on the other hand, closes its contact 80u2 and thereby

prepares the circuit for the rotary magnet Dm. In addition, due to the fact that relay B2 is energized by the changing over impulse, transmitted over the b-lead after this impulse series, the following circuit for relay F2 is set up: earth, contacts 95c3, 92p3, 91b2, 85a2, 83u2, 97b2, winding I of relay F2, battery, earth. Relay F2 remains energized in the following circuit after the release of relay B2: earth, contacts 96c3, 93p3, 90b2, 88f2, winding I of relay F2, battery, 85 earth.

The impulse receiving relay A2 of the final selector LW2 is intermittently energized and de-energized on the succeeding impulse series and thereby sets up the following circuit for the rotary magnet of the final selector: earth, contact 109a2, winding I of relay V2, contact 80u2, 101p2, winding of the rotary magnet Dm, battery, earth. The rotary magnet Dm and relay V2 are energized in this circuit. The switch 95 wipers of the final selector LW2 are set to the required subscriber's line according to the impulses transmitted. Due to relay V2 being re-energized in the above circuit the circuit for winding I of relay U2 is cut off due to the opening of contact 107v2. Relay U2, however, remains energized in the following circuit during the impulse series: earth, contacts 95c3, 92p3, 90b2, 88f2, 87f2, 86a2, 83u2, 82u2, 81r2, 75v2, winding II of relay U2, battery, earth. Relay 105 V2 is first deenergized at the end of this impulse series and is followed by relay U2. Relay P2 is unable to carry out the testing operation due to the fact that the test circuit, closed in the local traffic, is cut off by the opening of contact 89f2. In order to initiate the testing operation at the toll position FP depresses the key FT and thus applies a potential to the b-lead. Relay B in the repeater Ue is then energized in the following circuit: earth, battery, 110 key FT, plug St, jack K1, b-lead, lower primary winding of the repeater Ue, winding of relay B, contacts 34y, 35s, earth. It should be noted that at the beginning of the second impulse series for the setting of a final selector LW2, relay Y in 115 the repeater Ue was energized in the following circuit: earth, contacts 18c, 14v, 13v, 11s, 9y, 7h, 10a, winding I of relay Y, battery, earth.

Relay V is placed in the following locking circuit: earth, contacts 18c, 21y, winding II of relay Y, battery, earth. Relay B, when energized, closes its contact 28b and thereby sets up the following circuit for relay B2 in the final selector LW2: earth, battery, contact 28b2, lower secondary winding of the repeater Ue, b-lead, contact 41p1, b-wiper of the toll group selector FGW, junction line VL, contact 61y, winding I of relay B2, earth. Relay B2 in the final selector LW2 is energized and closes the following circuit for relay P3: earth, contacts 119b2, 120b2, 135 74f2, winding I of relay P3, contacts 93b2, 97b2, winding I of relay F2, battery, earth. Relay P3 is energized if the subscriber's line is idle or seized for a local call and is placed in the following locking circuit: earth, contacts 95c3, 93p3, 94p3, winding II of relay P3, rotary off-normal contact 78w2, winding of vertical magnet Hm, battery, earth. The vertical magnet Hm is not energized in this circuit.

If the subscriber's line is seized for a toll call, 145 relay P3 is unable to respond due to the fact that direct earth is applied to the c-lead and relay P3 is consequently short circuited over contacts 69p2, 71f2, 72f2 of the other final selector set to the line of the subscriber Tn in the 150

manner described below. The operator at the toll position FP, in such a case, receives the busy signal over: earth, winding of transformer Es, condenser Cp, rotary off-normal contact 121w2, 5 contact 122p2, winding II of relay A2, winding II of relay B2, contacts 84u2, 84a2, 91b2, 92b3, 95c3, earth. The busy signal is inductively transmitted to winding I of relays A2 and B2 and thence to the toll operator's position FP.

10 It will first be assumed that the required subscriber's line T_n is idle. In such a case relay P3 is energized and maintained in this condition in the manner described above. Relay V2 is energized over: earth winding II of relay V2, 15 contact 112p3, battery, earth. This relay opens its contact 114v2, and thereby breaks the automatic call signal provided for local traffic over the time switch SS and winding I of relay R2. The locking circuit for winding I of relay F2 is 20 cut off by the opening of contact 92p3. Relay F2 which was maintained energized over winding I of relay P3 while the key FT was depressed is energized as soon as the key FT is released. A test circuit for relay P2 is prepared by the 25 closing of contact 92p3. The required subscriber's line being idle, relay P2 is immediately energized in the following circuit: earth, contacts 95c3, 93p3, windings II and I of relay P2, c-wiper of the final selector LW2, battery, earth 30 in the preselector of the subscriber T_n . Its contacts 58p2 and 57p2 switch through to the two speaking leads. The high resistance winding II of relay P2 is short-circuited when contact 69p2 is closed and the seized line is guarded in this 35 manner. The following locking circuit for winding III of relay P2 is set up when this relay is energized: earth, winding II of relay F2, winding III of relay P2, contacts 111p8, 100p2, winding of rotary magnet Dm, battery, earth. The 40 rotary magnet Dm is not energized in this circuit but relay F2 is reenergized, in addition to relay P2. Relay F2 closes its contacts 71f2 and 72f2 which causes earth to be applied direct to the c-lead over these contacts and over contact 45 69h2 for the purpose of guarding against another toll connection. In order to call the subscriber the operator again throws over the key FT. This causes relay B2 in the final selector LW2 to be energized as described above. The 50 following circuit for relay R2 is then completed: earth, contact 119b2, winding II of relay R2, contact 100p2, winding of rotary magnet Dm, battery, earth. The rotary magnet is not energized in this circuit. Relay R2 applies ringing 55 current to the speaking leads over the following route: earth, ringing current source of supply RQ, contact 64r2, winding I of relay Y2, contact 57p2, b-wiper of the final selector LW2, contacts 58p2, 52y2, battery, earth. The winding II of relay Y2 is short-circuited by contact 63r2 during the ringing current transmission. When the subscriber lifts his receiver a direct current circuit is closed in which relay y2 is energized. Relay Y2 closes its contact 51y2 and thereby 60 switches through the a-lead and places winding I of relay A2 in the direct current circuit extending over the subscriber's loop. Relay A2 is energized and switches through the b-lead due to the actuation of its contact 58a2. Relay B2 is disconnected from the b-lead by the opening of contact 61y2 so that the transmission of ringing current is discontinued. The two speaking leads are thus switched through after relay R2 65 has been released.

70 If the subscriber is engaged in a local call,

relay P2, after the energization of relay P3, cannot be energized due to the parallel connected low resistance winding I of relay P2 of the other final selector set to the same subscriber's line. Due to contacts 59p3 and 60p3 being closed the toll operator at the position FP is able to speak to the subscriber T_n engaged in a local call and to advise him of the arriving toll call and, at the same time, request him to cut off the local connection. If the subscriber does not comply with the operator's request she depresses the key FT afresh and causes relay B2 in the final selector LW2 to be reenergized. This causes earth to be applied to the a-lead of the final selector LW2 in the following circuit since the relay F2 80 has been released due to the energization of relay P3: earth, contacts 119b2, 120b2, 73f2, 59p3, earth. Applying earth to the a-lead causes the impulse receiving relay A3 in the first group selector IGW to be short-circuited if the subscriber T_n was the caller in the local connection. This causes the release of the connection in known manner. If, on the other hand, the subscriber was the called party in the local connection, relay Y2 connected to the b-lead and 85 associated with the other final selector is short-circuited and thus caused to release due to earth being applied to the a-lead. The release of relay Y2 causes the a-lead to be cut off at contact 51y2 so that relay A2 also releases. This 90 short-circuits winding I of relay P2, energized in a local connection, due to the releasing contact 67a2 and the closed contact 70v2. Relay P2 of the final selector releases and opens its contact 69p2 so that the called subscriber T_n will be 95 disengaged. Relay P2 of the final selector LW2 is now able to operate.

The further switching operations have already been described above.

When, after the end of the conversation, the 100 subscriber replaces his receiver, the two feeding bridge relays Y2 and A2 of the final selector LW2 are released. The final selector, however, is not yet released and, moreover, the clearing signal is first transmitted to the toll position FP 105 by the following circuit for relay S in the repeater Ue being set up on the release of relay Y2: earth, winding I of relay B2, contact 61y2, junction line VL, b-wiper of the toll group selector FGW1, contact 41p1, lower secondary winding of the repeater Ue, contact 29v, winding of relay S, battery, earth. This causes the following circuit for relay SZ at the toll position FP to be closed: earth, contacts 35s, 34y, winding of relay B, lower primary winding of the repeater 110 115 Ue, b-lead, jack K1, plug St, winding of relay SZ, plug St, jack K1, a-lead, upper primary winding of the repeater Ue, winding of relay A, battery, earth. Relays A and B are not energized in this circuit but relay SZ at the toll position FP, on the other hand, is energized. Relay SZ causes a lamp to be lighted which thus gives the operator a signal indicating that the conversation is ended. When the operator now withdraws the plug St from the jack K1, relay C in the repeater Ue is released. Contact 18c, 120 therefore, is opened and cuts off the locking circuit for relays H and Y. Due to the opening of contact 26c, the test circuit to the toll group selector FGW1 is cut off, causing relay C1 to 125 release. The test circuit to the final selector LW2 is cut off when contact 42c1 in the group selector FGW1 is opened. Relay P1 in the toll group selector FGW1 is released and initiates 130 the general release in known manner.

150

- Relay C2 in the final selector LW2 is now released and by opening contact 95c3 breaks the locking circuit for winding II of relay P3. This relay relapses and by means of contact 111p3 5 cuts off the locking circuit for relays P2 and F2. The following circuit for the rotary magnet Dm is completed when relay P2 is released: earth, off-normal contact 108k2, contacts 107v2, 102c2, 103u2, 101p2 winding of rotary magnet Dm, battery, earth. Contacts 105d2 and 106d2 10 are closed on the energization of rotary magnet Dm. This completes the following circuit for relay U2: earth, contacts 108k2, 107v2, 106d2, 105d2, winding II of relay U2, battery, earth. 15 Relay U2 is energized and opens its contact 103u2. The circuit for the rotary magnet Dm is thus cut off. The rotary magnet Dm releases and in turn reopens contacts 106d2 and 105d2. Relay U2 is deenergized and recloses the circuit 20 for the rotary magnet. Relay U2 and the rotary magnet Dm thus interact in the manner described above after the manner of a relay interrupter and advances the switch step by step to its original position in which the off-normal contact 108k2 is opened and the switch is finally brought to rest. The locking circuit for relay P3 is cut off on the release of relay C2 due to the 25 opening of contact 95c3.
- The switching operations in the final selector 30 LW2 in the case of a local call will now be briefly explained. A local call is characterized by the absence of the additional impulse between the two impulse series for the setting of the final selector. Therefore, relays B2, F2, and P3 35 cannot be energized. At the end of the impulse series for this setting operation the following test circuit is closed during the release period of relay U2: earth, contacts 95c3, 92p3, 90b2, 89f2, 85a2, 83u2, 82u2, 81r2, 76r2, windings II and I 40 of relay P2, c-wiper of the final selector LW2, battery, earth, in the subscriber's Tn preselector. If the subscriber's line is idle, relay P2 is energized and switches through the two speaking leads as described above. The high resistance winding II is short-circuited by the closing of 45 contact 69p2 and the seized line is guarded against other seizures in known manner. The circuit for the rotary magnet Dm is opened by the opening of contact 101p2. The following 50 circuit for the ringing relay R2 is closed when, during the release period of relay U2, contact 100p2 is closed: earth, interrupter LU, contacts 117u2, 118b2, winding II of relay R2, contact 100p2, winding of rotary magnet Dm, battery, earth. The rotary magnet Dm is not energized 55 in this circuit. Ringing current is now applied in the manner described in connection with a toll call. If relay U2 has been released, relay R2 is energized in the following circuit for the repeat 60 call: earth, time switch SS, winding I of relay R2, contacts 114v2, 99p2, 100p2, winding of rotary magnet Dm, battery, earth. The rotary magnet is not energized in this circuit. If the subscriber lifts his receiver in a ringing pause, 65 the energizing circuit for relay Y2 extends as follows: earth, contact 62r2, windings II and I of relay Y2, contact 57p2, b-wiper of the final selector, LW2, subscriber's line loop, a-wiper of the final selector LW2, contacts 58p2, 52y2, battery, earth. Relay Y2 is energized and in addition to causing the switching operations described in connection with the setting up of a toll call breaks the circuit for the ringing relay R2, controlled over the interrupter LU, due to 70 the opening of contact 116y2. Contact 115y2, 75

at the same time, closes the following circuit for relay V2; earth, winding II of relay V2, contacts 115y2, 118b2, winding II of relay R2, contact 100p2, winding of rotary magnet Dm, battery, earth. The rotary magnet Dm is not energized in this circuit. Relay V2, by the opening of contact 114v2, cuts off the circuit for the ringing relay R2 controlled by the time switch SS. In addition it is placed in a locking circuit over contacts 113v2 and 99p2 independent of relay Y2. 80

The final selector is released when the calling and called subscribers replace their receivers. This causes relay C2 to release and, in addition, causes the release of the two feeding bridge relays Y2 and A2. Winding I of the test relay P2 is short-circuited over contacts 68c2 and 67a2. Relay P2 restores and causes the release of the final selector in the same manner as that applied in the case of a toll call. 85

Finally, the case will be considered in which the called subscriber Tn has not replaced his receiver at the end of the toll call, while the toll operator at the position FP withdraws the plug St from the jack K1. Relays C2 and P3 in the final selector LW2 are released in the manner already described. P3 opens its contact 111p3 and thereby cuts off the locking circuit for winding III of relay P2 and winding II of relay F2. Relay F2 is then released but the slow-acting relay P2 still remains energized even after the short circuit for its winding I has been removed in the following circuit due to the opening of contacts 71f2 and 72f2: earth, contact 69p2, winding I, c-wiper of the final selector LW2, 100 battery, earth in the subscriber's preselector. The subscriber Tn is, therefore, no longer engaged in a toll connection due to the fact that the earth applied direct to the c-lead is disconnected by the release of relay F2. On the other hand, due to the low resistance winding I of the test relay P2 being connected to the c-lead his line is guarded in known manner against an incoming local call. His line, therefore, may be seized afresh for an additional toll call even if he has not replaced his receiver. 100

What is claimed is:

1. In a telephone system in which low value and high value connections are extended to called lines over the same connecting devices, means responsive to a connection for guarding a line against subsequent connections of one or both values depending on the value of the first connection, and means responsive to the release of the calling party from a high value connection prior to the release of the called party therefrom for changing the line guarding to correspond with that of low value connections. 125
2. In a telephone system in which low value and high value connections are extended to called lines over the same connecting devices, means effective in a low value connection for guarding a line against subsequent low value connections, means effective in a high value connection for guarding a line against subsequent connections of either high or low values, and means responsive to the release of the calling party from a high value connection prior to the release of the called party therefrom for removing the guard against subsequent high value connections without releasing the connecting devices involved in the first connection. 135
3. In a telephone system, an automatic switch, a called line, means for operating the switch to 150

extend a connection of either of two classes to the line, means effective in a connection of one class for guarding the line against a subsequent connection of that class, means effective in a party therefrom for removing the guard against subsequent connections of said other class while maintaining the guard against subsequent connections of said one class.

5 connection of the other class for guarding the line against subsequent connections of either class, and means controlled jointly by the calling and called parties involved in a connection of said other class for removing the guard against 80

10 connections of the other class while maintaining the guard against connections of said one class. 85

4. In a telephone system, an automatic switch, a called line, means for operating the switch to extend a connection of either of two classes to the line, means effective in a connection of one class for guarding the line against a subsequent connection of that class while permitting subsequent connections of the other class, means effective in connections of the other class for 90

20 guarding the line against subsequent connections of either class, and means responsive to the calling party releasing from a connection of said other class prior to the release of the called 95
